(57) **CLAIM**

The ornamental design for a billboard optic, as shown and described.

DESCRIPTION

FIG. 1 is a perspective view of the billboard optic;

FIG. 2 is a front view of the billboard optic;

FIG. 3 is a back view of the billboard optic;

FIG. 4 is a left side view of the billboard optic;

FIG. 5 is a top view of the billboard optic; and,

FIG. 6 is a bottom view of the billboard optic.

The broken line disclosure in the views represents portion of the optic which form no part of the claimed design.
